UNITED STATES PATENT OFFICE.

JAMES R. STEVENS, OF HARTFORD, CONNECTICUT, ASSIGNOR TO ERNST SCIFALL.

DESIGN FOR A SPOON, &c.

SPECIFICATION forming part of Design No. 20,727, dated May 19, 1891.

Application filed April 7, 1891. Serial No. 388,051. Term of patent 3½ years.

To all whom it may concern:

Be it known that I, JAMES R. STEVENS, a citizen of the United States, residing at Hartford, in the county of Hartford and State of Connecticut, have invented and produced a new and original Design for Spoons, Forks, and the Like, of which the following is a specification, reference being had to the accompanying drawing, forming a part thereof.

10 The figure is a plan view of a spoon, showing my design.

In the accompanying fac-simile drawing, the letter *a* denotes the bowl of a spoon, *b* the handle, and *c* the shank, constructed, as shown, 15 of somewhat irregular outline. The spoon bears the pictorial representation of the familiar picture of Putnam leaving the plow, which represents a field in front of a house, with a plow in a furrow, the horses harnessed to the 20 plow being suddenly stopped by a man, and in the immediate foreground a mounted mes-

senger shown in the act of delivering a message of some kind to the man holding the plow-horses. In the background armed men are seen running toward the plow. In connection with this picture there is also shown projecting from a circular frame the picture of a wolf's head. Spaces are left on the handle and shank for the reception of any suitable inscription or marking, as of dates or 30 names.

I claim as my invention—

The design for a spoon, fork, or the like article of table-ware of somewhat irregular outline and bearing the pictorial representation 35 of the historical event of Putnam leaving the plow, as shown.

JAMES R. STEVENS.
